UNITED STATES PATENT OFFICE.

FREDRIC C. WEIR, OF CINCINNATI, OHIO.

HEAD-CHAIR FOR RAILWAY-SWITCHES.

SPECIFICATION forming part of Letters Patent No. 351,234, dated October 19, 1886.

Application filed March 16, 1886. Serial No. 195,443. (No model.)

To all whom it may concern:

Be it known that I, FREDRIC C. WEIR, of Cincinnati, in the county of Hamilton and State of Ohio, have invented certain new and 5 useful Improvements in Head-Chairs for Railway-Switches, of which the following is a specification.

My invention relates to an improved head-chair for railway-switches.

10 The object of my invention is to provide a cheap, firm, and durable device, all of which will be set forth in the description of the accompanying drawings, making a part of this specification, in which—

15 Figure 1 is a perspective view of my improvement. Fig. 2 is a bottom perspective view of the cutter lip or lug. Fig. 3 is a detail view of the spacing-bar. Fig. 4 is a perspective view of one of the side lugs.

20 A represents the bed-plate of the chair.

B represents the side lugs between which the switch-rail moves. These lugs are rigidly secured to the bed-plate by rivets or other suitable means.

25 C represents the spacing-bar. Its ends are provided with gains c, and are held down by the overlapping of the side lugs, B.

D represents the cutter lip or lug. The forward end is provided with a shoulder, 1, and 30 an overhanging flange, 2. The shoulder 1 rests firmly against the spacing-bar C, and the flange 2 projects over the top to assist in holding the same in position. The outer edges, 4 and 5, of the cutter-lug D are gained or rounded off, so as to fit the upper and inner surfaces of the flange of the two rails, which abut under the lip or lug D.

35 E F represent side lips, which are securely

riveted to the base-plate A. The inner edges of both of these lips are respectively upturned 40 and shaped to fit the recess upon the outer surface of the flange of the rails.

a b represent the space occupied by the two rails upon either side of the central lug, D.

The lips of the lugs D E F rest upon and 45 firmly hold the main rails in position, and the switch-rail is held in either of its extreme positions alternately by the lugs B B, and the moving switch-rail and fixed rails are held against longitudinal movement by the spacing- 50 bar C, against which they respectively abut. By this means a head-chair is produced that is more elastic as a joint-chair for the switches, and in consequence the life of the switch-rails is prolonged, and at the same time a firm and 55 sufficiently rigid joint is obtained.

I claim—

1. A head-chair composed substantially of the base-plate A, to which is securely fastened the parts B C D E F, substantially as specified. 50

2. In a head-chair, the spacing-bar C, secured thereto by one or more of the middle lips, D, and the side lugs, B B, substantially as specified.

3. In a head-chair, the spacing-bar C, secured 65 thereto by one or more of the middle lips, D, and the side lugs, B B, each provided with abutting shoulders and overhanging flanges, substantially as specified.

In testimony whereof I have hereunto set 70 my hand.

FREDRIC C. WEIR.

Witnesses:

ROBERT ZAHNER,
M. E. MILLIKAN.
